SLIDE NECKTIE

John Henri Waidelich, 404 Mayfair Blvd.,
Columbus, Ohio

Filed Apr. 24, 1964, Ser. No. 79,689

Term of patent 14 years

(Cl. D3—16)

FIG. 1 is a plan view of a slide necktie showing my new design; and

FIG. 2 is a view in section taken along the line 2—2 of FIG. 1.

I claim:

The ornamental design for a slide necktie, as shown.
